UNITED STATES PATENT OFFICE

GASTON VAN COPPENOLLE, OF ROCHECORBON, FRANCE

SPINNING APPARATUS

Application filed May 2, 1928, Serial No. 274,579, and in France July 13, 1927.

This invention relates to spinning apparatus of the kind in which the yarn is twisted by a driven flyer device and a winding-on device to which an adjustable drag 5 is applied, and the object of the invention is to provide an improved spinning apparatus of this type.

According to the invention, the spinning apparatus comprises a flyer provided with 10 yarn guides mounted to slide freely in vertical guides on the flyer so as to be capable of hanging on the yarn and a drag brake consisting of a freely mounted roller upon which a part of the bobbin bears.

15 The accompanying drawing shows, by way of example, one form of the invention:

The figure is a vertical longitudinal section of the complete device constructed according to my invention.

20 In a cross bar 1 fixed to supports cast in one with the frame is tightly held a hard bronze collar 2 with lubricating cup. This collar is provided with oil ways 3 and 4.

Upon the upper shoulder of the collar and 25 cup rests the flyer or winding tube 5 of cement steel, hardened and rectified at the part working in the collar and cup.

The flyer is fixed to a V-groove pulley 6 of suitable diameter, tapped and tightly 30 screwed in the direction of rotation. This pulley is driven from a driving element known as a "drum" on which cords or bands are mounted in the usual manner.

On the lower end of the collar 2 is fixed a 35 screw threaded bronze ring 8 which serves to guide the flyer and at the same time forms the connection between the oil circulation conduits.

On the upper part of the flyer is mounted 40 a guide ring 9 in which holes 10 and 11 are formed to receive yarn guides 12 and 13 which are adapted to slide in the holes 10 and 11 whose weight is adjusted in accordance with the count of the thread as herein-

45 after explained. Below the holes, are arranged two guide ribs 14 and 15 which form grooves for maintaining the yarn guides in place and for preventing them from pivoting on themselves.

50 Above the guide ring 9 is mounted another

guide ring 16 of bronze and this is also formed with holes 10 and 11 for the yarn guides but if the count of the thread is such that very light yarn guides are required this element may be omitted.

The rings 9 and 16 can be adjusted and fixed by means of screws 17 and 18 in the required position in a groove 19 formed in a suitable part of the flyer.

On the cross bar 1 is fixed a support 20 for the independent brake for the flyer. This support is fixed to the cross bar by means of a square headed screw 21 which also holds the collar by means of a bore-hole cut therein. Further, it is held in its fixed position by a pin 22. In the support is mounted a bush 23 with internal square screw threads and against this bush is another bush 24 with screw threads ad hoc.

The hand control 27 is fixed to the bush 24 by means of two grub screws 25 and 26.

The two bushes are connected by a threaded shaft 28 to one end of which is riveted a jaw 29 carrying a fibre or leather crescent 30.

On the lower cross piece 31 secured or fixed 75 on feet or supports cast in one with the frame is fixed a vertical steel spindle 32 which is screwthreaded at its lower part. Under the shoulder on this spindle is disposed a gudgeon or prisoner 33. This spindle is fixed by 80 two nuts 34 and 35.

The upward and downward movement of the platform is ensured by two vertical shafts or uprights 36 working in a bronze socket 37 provided with an oil cup and cut away at the 85 upper part of its bore.

The uprights may also be guided at their upper parts by means of a support provided with a bronze socket and fixed to the frame.

On a screw threaded part at the end of the 90 uprights is fixed a support 38 and this support is held in machined shoulders or collars 39 and 40 which hold the platforms 41 firmly in position.

On the platform rests a shouldered bronze 95 bush 43 in which is fixed the brass sleeve 44 which forms the intermediate part of the bobbin-carrier. This sleeve bears on the spindle at its ends only so as to diminish the friction between the contacting parts and at the same 100

time to form a lubricating chamber. On the upper end of this sleeve is mounted a threaded bush 45 on which the bobbin 46 rests. At the bottom of the sleeve on the inside a cut 5 is made to form a lubricating cup. A pin 40 adapted to be engaged in any one of four holes in the platform 41 holds the bush 43 against rotation. The bobbin moves freely on its spindle to follow the alternate movement of the bobbin-carrier and its lower foot or flange.

10 The shape and diameter to ensure the regular and normal working of the friction roller 47 in the course of its circumvolution on the circumference of the said flange during each course.

The friction roller is of hardened cement steel. It is free on the spindle 48 and can move slightly up and down on the spindle for the purpose of eliminating wear. The

20 bore of the roller is slightly widened at one end to facilitate the flow of oil. The friction roller is held simply by the pin 49 which is forced into the hole 50 and bent upon itself above the spindle. The simultaneous rotation of the friction roller and the lower flange of the bobbin prevent wear of these elements.

25 The small spindle 48 may be forged and fitted in the piece or simply threaded before hardening and screwed into the upper shoulder 51 of the brake rod or bar 52.

If the brake is mounted by means of a steel rod of suitable section, the shoulder of the spindle is simply turned or shrunk onto the piece.

30 On the flanged bush 45 is fixed a slide 53 in which the brake bar 52 works. This slide is formed as a ramp to cooperate with a cam projection 54 on the brake bar.

35 A small spring 55 fixed in a groove 56 in the sleeve 44 and acting on the brake bar 52 serves to press the cam projection 54 against the ramp formed in the slide 53.

40 Further the guiding of the lower part of the brake bar is ensured by a slide piece 57 soldered to the slide 44. The brake bar is fixed at its lower part by a square piece 58 sliding in a groove formed in the bush 43. The bar and this piece are connected by 50 means of two screws 59 disposed in the same plane.

45 In a slide 60 of the support 58 is placed a stop bolt 61 which passes through the piece 62 fixed in a groove in the piece 43 and held 55 in position by the screwed pin 42. On the piece 62 rests the nut 63 which ensures the fixing of the brake roller after final adjustment on the bobbin flange. The wing nut 64 is employed to effect displacement of the 60 brake rod and thus to enable the roller to be given the degree of friction necessary for normal winding by the displacement of the rod 54 in the slide 53.

65 A square or a piece cast in one with the platform 41 may be placed in front of the

platform to serve as a support for a bobbin-carrying spindle in order to ensure facility for the spinning operative to replace the bobbins with empty ones as soon as they are filled. This support 65 carries a spindle 67 which is fixed by a nut 68. The replacement bobbin 69 rests on the spindle shoulder and is disposed between each bobbin carrier conveniently to the hand of the operator.

70 In the operation of the apparatus, the spinning operative stops the winder by means of the hand brake at the beginning of the winding operation. Then she breaks off a thread end of a certain length from a full bobbin and winds this by hand on the outer part of the bobbin. She then passes the thread through one of the yarn guides and releases the winding brake with her right hand still holding the thread in the fingers of her left hand. She adjusts the drag by lightly braking the bobbin through the roller by the regulating screw and as soon as she feels that the reaction of the said roller is sufficient for normal winding without undue tension she makes the connection.

75 She then makes the final adjustment to bring the thread coming from the cylinder to the level of the scrolls with her right hand whereupon she tightens the set screw of the regulator. The bobbin is then wound normally to the end even if there are accidental breakages as the balance between the effort and resistance is always ensured by the opposing and instantaneous reaction of the friction roller.

80 In setting up the apparatus after the two cross bars have been fixed exactly in a vertical plane, the trued spindles 32 are engaged in the feathers in the lower cross bar and fixed by means of the nuts 34 and 35. Then the sockets 37 are mounted and the uprights 36 set up after which the supports for the platform 38 are screwed in the rod. The platforms 41 are then placed on their supports.

85 To mount the bobbin carrier, it is only necessary to introduce the brake bar into the slide 53 after having first placed the springs 55 in position, screw the sleeve 44 to the bush 45 and then screw the lower end of the sleeve into the socket 43 in its thread, fix the support 58, place the square 62 in position and connect it to the bolt 61 of the brake regulating mechanism.

90 The brackets 65 for the replacement bobbins and also the spindles 66 can then be set up.

95 The collars 2 are then fixed in the upper cross bar 1. This latter must be mounted with great care. The winders 5 with their rings 9 and 16 are placed in position and then the lower nuts of the collars and the V-pulleys are screwed on. The yarn-guides 12 and 13 are placed in position and the supports for the winding brake 20 are set up.

and also the screwed bushes 23 and 24, the handle 27, the spindles 28 and jaws 29 and the fibre or leather crescents 30.

- This arrangement is of simple design and 5 is free from vibration and has the maximum protection from centrifugal reaction by reason of its position and form. Its true vertical mounting, the ease with which it can be balanced and its rotation on parts which 10 are strictly aligned in a bronze collar which provides for lubricating by continual circulation of oil permits of very high speeds without fear of heating of the contacting parts.
- 15 The vertical position of the tube also enables the machine to work all day without stopping, the removal of the bobbin when filled being effected in one operation and without any difficulty by the use of the individual brake which is placed ready to hand 20 at the lower part of the tube.

In the position which it occupies in this arrangement, the winding angle is straightened to the maximum degree and this position 25 considerably reduces the effect of centrifugal force on the yarn.

The slight ballooning which can still take place under conditions of very high speed in the parts which are not guided can be 30 exactly balanced at the desired elastic tension by the practical determination of the weight of the yarn guides which are movable and capable of regulation and which work freely in bronze slides which are capable of 35 displacement in a groove and are fixed by means of a screw as shown in the accompanying drawing.

It is also possible, notwithstanding the short distance between the delivery cylinder 40 and the scrolls due to the free vertical position of the tube, to interpose a movable thread guide very near to the extreme winding point thus almost completely preventing ballooning at the greatest speeds of rotation 45 of the tube.

The tube is driven in the usual manner by means of a tin roller and V-pulley and the direction of rotation can easily be reversed to produce reverse twist by simply crossing 50 the driving ropes or bands.

The bobbin carrier follows the alternating movement of the carriage which is controlled in the usual manner by a heart cam with balancing counterweights or by a piece known 55 as a "lantern".

The arrangement as designed is not dangerous and cannot cause an accident when working in spite of the high speeds which can be attained.

60 I claim:

A spinning apparatus of the kind referred to, comprising in combination a flyer or winding tube, yarn guides carried by said flyer, vertical guides on the latter wherein 65 said yarn guides are freely slideable so as to

be capable of hanging on the yarn, a bobbin in said flyer, and a freely mounted friction roller engaging said bobbin for dragging same, substantially as set forth.
